COMBINED TIE RACK AND DRAWER

Joseph H. Lane, Chattanooga, Tenn., assignor to
 Cavalier Corporation, Chattanooga, Tenn., a
 corporation of Tennessee

Application August 26, 1938, Serial No. 227,003

8 Claims. (Cl. 45—7)

This invention is a novel combined drawer and tie-rack and the principal object is to provide a tie-rack hingedly mounted within the drawer so that when the drawer is pulled into open position the tie-rack may be swung from normal position lying upon the bottom of the drawer, into suspended position at the front or at the side of the drawer in which position the ties may be readily placed on or removed from the rack. Ordinarily, ties which have been placed in a drawer become badly rumpled when one is removed, even though the ties may have been placed flat on the drawer bottom; moreover the lowermost ties are not easily accessible.

In my invention the tie-rack normally rests on the drawer bottom and is pivoted on a bail so that when the drawer is opened the tie-rack may be lifted out of the drawer and will hang in suspended position at the front or at the side of the drawer, whereby the ties can be taken off or placed upon the rack at will, and when the rack is replaced in the drawer the ties and rack will lie flat therein.

I will explain the invention with reference to the accompanying drawing which illustrates several practical embodiments thereof, to enable others to adopt and use the same; and will summarize in the claims the novel features of construction, and novel combinations of parts, for which protection is desired.

In said drawing:

Fig. 1 is a perspective view of a drawer partly broken away to show one modification of my novel tie-rack in normal position therein lying upon the drawer bottom.

Fig. 2 is an enlarged plan view of a portion of the drawer, showing the rack carrying the ties in position therein, resting upon the drawer bottom.

Fig. 3 is a vertical sectional view on the line 3—3, Fig. 1, showing the drawer pulled into open position in the article of furniture, and showing the tie-rack suspended at the front of the drawer.

Fig. 4 is a perspective view showing a modification in which the tie-rack is mounted so as to be swung over the side of the drawer, when opened, rather than over the front end of the drawer.

My novel tie-rack 1 may be of wood, metal, or other desired material, and is provided at one end with a spaced parallel bar 2 upon which the ties T (Fig. 2) may be suspended in the usual manner. At the opposite end of the tie-rack is a handle 3 whereby the rack may be lifted out of the drawer D in which it is pivotally mounted.

The drawer D may be of any desired construc-

tion, and may be used in any kind of furniture, although same is preferably used in wardrobe furniture such as chiffoniers, bureaus, or the like. As shown, the drawer D is provided with a partition D' forming a compartment D2 of slightly greater width than the tie-rack 1. The tie-rack 1 is of somewhat shorter length than compartment D2, and is mounted within said compartment by means of a hinged bail 4, preferably of U-shape, the base 4a of the bail passing through aligned bores in the supports for bar 2. The legs 4b of the bail are normally disposed substantially parallel with the sides of the tie-rack 1 and the outer ends of the legs 4b are bent outwardly as at 4c to engage holes in the partition D' and in the adjacent wall of the drawer D, whereby the bail 4 is hingedly mounted within the drawer permitting the tie-rack 1 to be pulled upwardly and outwardly so as to lie suspended against the front wall of the drawer, as shown in Fig. 3, or against a side wall of the drawer as shown in Fig. 4. Preferably the legs 4b are of such length, and the pivots 4c are so disposed that the tie-rack 1 will normally lie flat on the bottom of the compartment D2, as shown in Figs. 1 and 3. The partition D' may be omitted, if desired, and suitable blocks may be provided in the drawer for receiving the pivots 4c of the bail. Also the bail 4 may be replaced by any other desired form of support which will permit the rack to lie substantially flat within the drawer and also to be suspended from the front of the drawer when the latter is opened.

When it is desired to remove or insert a tie, the drawer is pulled out from the furniture F, and the rack 1 lifted by means of a handle 3 and pulled outwardly, the bail 4 pivoting on the members 4c so that when the tie-rack is in the position shown in Fig. 3, bail 4 will rest upon the top of the front wall of the drawer, and the tie-rack 1 will be suspended vertically in front of the drawer, in which position the ties may be readily inserted or removed from the rack in the usual manner; or when the tie-rack is mounted so as to be suspended from a side of the drawer, as shown in Fig. 4, the bail 4 will rest upon the top of the said side wall.

After the ties have been thus removed or inserted, and while the drawer D is still open the rack may again be lifted and swung inwardly of the drawer so as to again enter the compartment D, and the rack will lie flat upon the bottom of the compartment, and in such position the ties on the rack will also lie flat therein, preventing

same from becoming rumpled. The drawer D may then be closed.

I claim:

- 5 1. In combination, a drawer, a tie-rack normally lying within the drawer, a handle at the front end of said tie-rack, a tie-supporting bar adjacent the opposite end of said tie-rack; and a U-shaped bail connecting the tie-rack and drawer permitting the tie-rack to be swung upwardly and outwardly of the drawer.
- 10 2. In a combination as set forth in claim 1, said bail having one end pivotally connected with the rack adjacent its inner end, and having its other end pivotally connected with the drawer.
- 15 3. In a combination as set forth in claim 1, said bail having its base pivotally connected to the rack adjacent its inner end, and having its legs normally extending parallel with the rack when in normal position within the drawer, the outer ends of the legs being hingedly connected to the drawer.
- 20 4. In combination, a drawer having front and side walls, a tie-rack normally lying within the drawer, a handle at the front end of said tie-rack, a tie-supporting bar adjacent the opposite end of said tie-rack; and a U-shaped bail connecting the tie-rack and drawer and permitting the tie-rack to be swung upwardly and outwardly

of the drawer into suspended position adjacent a wall of the drawer.

5 5. In a combination as set forth in claim 4, said bail having one end pivotally connected with the rack adjacent its inner end, and having its other end pivotally connected with the drawer.

6. In a combination as set forth in claim 4, said bail having one end pivotally connected with the rack adjacent its inner end, and having its other end pivotally connected with the drawer, 10 said bail being of length to engage the top of the wall of the drawer when the tie-rack is suspended.

7. In a combination as set forth in claim 4, said bail having its base pivotally connected with the rack adjacent its inner end, and having its 15 legs normally extending parallel with the rack when in normal position within the drawer, the outer ends of the legs being hingedly connected to the drawer.

8. In a combination as set forth in claim 4, said 20 bail having its base pivotally connected with the rack adjacent its inner end, and having its legs normally extending parallel with the rack when in normal position within the drawer, said legs being of length to engage the top of the wall of 25 the drawer when the tie-rack is suspended, and the outer ends of the legs being hingedly connected to the drawer.

JOSEPH H. LANE.
